CAFE ROD DRAPERY HOOK

David Wolf, Newton, Mass., assignor to Empire Slip-On Hook Corp., Watertown, Mass., a corporation of Massachusetts

Filed Oct. 19, 1965, Ser. No. 87,594

Term of patent 14 years

(Cl. D21—1)

Fig. 1

Fig. 3

FIG. 1 is a front elevational view of a cafe rod drapery hook showing my new design; and

FIG. 2 is a side elevational view looking from the left of FIG. 1; and

FIG. 3 is a rear perspective view thereof.

I claim:

The ornamental design for a cafe rod drapery hook, as shown.
